BOTTLE STOPPER

Richard B. Teamer, Somerville, N. J.

Application September 5, 1935, Serial No. 39,267

4 Claims. (Cl. 215—28)

This invention relates to bottle stoppers of the non-refillable type.

An object of this invention is a bottle stopper of the non-refillable type which can be easily and permanently secured to the neck of a bottle, which is of simple construction, cheap manufacturing cost and highly efficient and which will pour a steady and equal stream in all pouring positions.

Other objects, novel features and advantages of this invention will become apparent from the following specification and accompanying drawing, wherein:

Fig. 1 is a fragmentary section of a bottle equipped with a stopper embodying the invention, the bottle being in vertical position and the parts of the stopper being in bottle-closing position;

Fig. 2 is a similar view with the bottle tipped and the parts of the stopper in pouring position, and

Fig. 3 is a similar view with the bottle in horizontal position and the stopper parts being in bottle-closing position.

The stopper comprises a cap 10 which is connected to the bottle neck 11 in any suitable manner. In the embodiment shown, the bottom edge 12 of the cap 10 fits the neck 11 snugly and then is bowed outwardly to provide an annular groove 13. The bottle neck 11 is provided with a groove 14 from the upper edge of which extends the conical surface 15. A split resilient ring 16 is arranged in the groove 14 and prevents removal of the cap 10 from the bottle neck 11. In assembling the cap with the neck, the split ring 16 rides over the conical surfaces 15 at the same time expanding into the groove 13 and then contracts into the groove 14 and when in the groove prevents removal of the cap.

An annular gasket 17 rests on the upper edge 40 of the bottle neck and through the gasket 17 extends a metal sleeve 18 having a flange 19 resting on the top face of the gasket 17. The inner part of the flange 19 is conical while the outer part of the flange 19 is perpendicular to the axis of the sleeve 18. The conical portion of the flange 19 forms with the sleeve 18 a valve seat having a very narrow contact area.

A perforated cylindrical cage 20 has a flange 21 which engages the outer portion of the flange 19 and underlies a shoulder 22 formed in the cap 10. Within the cage 20 and resting on the valve seat above described is a hemispherical or other spherical segment member 23 which closes the sleeve 18 to flow of liquid into the bottle, but permits outward flow of liquid from the bottle. The

diameter of the hemispherical member 23 is greater than the distances from the edge of the valve seat to the top of the cage 20 so that the curved surface of the member 23 will always engage the valve seat, it being impossible for the member 23 to rotate sufficiently to disengage its curved surface from the valve seat.

When the bottle is in vertical position, the stopper parts are in the position shown in Fig. 1 with the member 23 seated on the valve seat and preventing the flow of liquid into the bottle. When the bottle is turned into any position past horizontal, such, for example, as the position shown in Fig. 2, the member 23 moves off the valve seat by gravity, thus permitting liquid to flow out of the bottle. However, as soon as the bottle is returned to horizontal position, the member 23 returns to engagement with the valve seat and prevents flow of liquid into the bottle. The return of the member 23 to closing position upon arrangement of the bottle in horizontal position is due to its hemispherical shape, for when its plane surface is vertical its center of gravity is offset from its point of support and gravity effects movement of the ball about its point of support as a fulcrum to bring its curved surface into engagement with the valve seat, as shown in Fig. 3. In such position, the plane surface of the member 23 is oblique to the stopper axis, but because of the previously described relation between the diameter of the member 23 and the distance between the valve seat and end of the cage 10, there will be engagement between the curved surface of the member 23 and the valve seat effective to close the end of the sleeve 18. The member 23 will move off the valve seat readily upon tipping of the bottle due to the narrow area of contact. Even though the liquid in the bottle be of a sticky nature, the weight of the member 23 will easily overcome any adhesion that may be developed by the liquid along the narrow contact area.

The upper end of the cap 10 is reduced in diameter and is formed with threads 24 to receive a threaded closure 25 of the ordinary type.

I claim:

1. The combination with a bottle neck of a cap, means for securing said cap to said bottle neck, an inwardly projecting shoulder in said cap, an annular gasket between the end of the bottle neck and said shoulder, a sleeve extending through said gasket and having a flange overlying the end surface of the gasket adjacent said shoulder, a cylindrical perforated cage coaxial with said tubular member and having a flange interposed between said shoulder and said sleeve

flange, and a spherical segment member in said cage having its curved surface engageable with the end of said tubular member.

2. The combination with a bottle neck of a cap, 5 means for securing said cap to said bottle neck, an inwardly projecting shoulder in said cap, an annular gasket between the end of the bottle neck and said shoulder, a sleeve extending through said gasket and having a flange overlying the end surface of the gasket adjacent said shoulder, a cylindrical perforated cage coaxial with said tubular member and having a flange interposed between said shoulder and said sleeve flange, and a spherical 10 segment member in said cage having its curved surface engageable with the end of said tubular member.
- 10 3. The combination with a bottle neck of a cap, 15 means for securing said cap to said bottle neck, an inwardly projecting shoulder in said cap, an annular gasket between the end of the bottle neck and said shoulder, a sleeve extending through said gasket and having a flange overlying the end surface of the gasket adjacent said shoulder, the inner portion of said flange being conical and overlying said sleeve, a cylindrical 20 perforated cage coaxial with said tubular member and having a flange interposed between said shoulder and said sleeve flange, and a spherical 25 segment member in said cage having its curved surface engageable with the end of said tubular member, said spherical segment member being greater in diameter than the distance between the end of said sleeve and the end of said cage.
- 20 4. The combination with a bottle neck of a cap, 25 means for securing said cap to said bottle neck, an inwardly projecting shoulder in said cap, an annular gasket between the end of the bottle neck and said shoulder, a sleeve extending through said gasket and having a flange overlying the end surface of the gasket adjacent said

shoulder, the inner portion of said flange being conical and overlying said sleeve, a cylindrical perforated cage coaxial with said tubular member and having a flange interposed between said shoulder and said sleeve flange, and a spherical 5 segment member in said cage having its curved surface engageable with the end of said tubular member.

4. The combination with a bottle neck of a cap, 10 means for securing said cap to said bottle neck, 15 an inwardly projecting shoulder in said cap, an annular gasket between the end of the bottle neck and said shoulder, a sleeve extending through said gasket and having a flange overlying the end surface of the gasket adjacent said shoulder, the inner portion of said flange being conical and overlying said sleeve, a cylindrical 20 perforated cage coaxial with said tubular member and having a flange interposed between said shoulder and said sleeve flange, and a spherical 25 segment member in said cage having its curved surface engageable with the end of said tubular member, said spherical segment member being greater in diameter than the distance between the end of said sleeve and the end of said cage.
